UNITED STATES PATENT OFFICE.

WLADYSLAW GULA AND MICHAEL J. GLOGOWSKI, OF THORNDIKE, MASSACHUSETTS.

OILING DEVICE.

1,402,857.

Specification of Letters Patent. Patented Jan. 10, 1922.

Application filed November 24, 1919. Serial No. 340,184.

To all whom it may concern:

Be it known that we, (1) WLADYSLAW GULA and (2) MICHAEL J. GLOGOWSKI, citizens of Poland, residing at Thorndike, in the 5 county of Hampden and State of Massachusetts, have invented certain new and useful Improvements in Oiling Devices, of which the following is a specification.

The primary object of the invention is 10 the provision of an oiling device or lubricating systems serviceable in connection with a plurality of bearings and being in the nature of a readily controlled gravity feed system of lubrication and readily employed 15 in connection with a spinning machine for lubricating the spindles thereof.

A further object of the invention is the provision of an oiling device especially adapted for spinning machines whereby the 20 plurality of spindles are uniformly lubricated, the lubrication being readily controlled manually for varying the degree of feed as well as interrupting the same to any one of the spindles when found desirable.

With these general objects in view, the 25 invention consists of the novel combination and arrangement of parts hereinafter more fully described in connection with the accompanying drawings and then claimed.

In the drawings, like reference characters 30 designate corresponding parts throughout the several views, and

Figure 1 is an elevation view of the invention assembled in connection with the spindles of a spinning machine,

Figure 2 is a top plan view thereof,

Figure 3 is a sectional view taken upon line III—III of Fig. 1,

Figure 4 is a longitudinal sectional view 40 through the lubricating feed pipe,

Figures 5 and 6 are transverse sectional views taken upon lines V—V and VI—VI of Fig. 4,

Figure 7 is an elevational view of one 45 of the controlling sleeves, and

Figure 8 is an end view thereof.

Referring more in detail to the drawings, our invention broadly provides an oil or lubricant receiver 10 emptying into a hopper 50 per 11 therebeneath, the said hopper being in communication with a main oil line 12 adapted for lubricating the spindles 13 of the spinning machine. Stub pipes 14 formed of flexible material, preferably lead or copper, lead from the base or journal 15 to the 55 spindles 13, a connection 16 having a valve

17 being provided between each journal 15 and its feed tube 14.

The oil reservoir 10 receives the lubricant and has a closure cap 18 for the outlet opening 19 in the bottom of the reservoir, said cap being secured for operation to a wire 20 frictionally secured in guides 21 upon the container 10 and operable by a handle 22 at the top thereof. A glass 23 in the side of the container 11 shows the elevation of the oil at a glance while the cap 18 is readily manipulated to open and close the outlet 19 by means of the handle 22.

A pipe 24 receives the discharge lubricant 70 from the cup or hopper 11 and is connected to the oil line 12 whereby as will be evident, the oil from the cup 11 runs by gravity into the line pipe 12.

A sleeve 25 is provided for each stub pipe 75 or feed tube 14, said sleeves having telescoping ends 26 and being journaled upon the line pipe 12 as best illustrated in Figure 4 of the drawings. Outlet openings 27 spaced apart in the upper side of the line 12 are 80 adapted to supply lubricant therethrough to the stub tubes 14 by means of perforations 28 in the sleeves 25, the lower ends of the tubes 14 being adapted for detachable connection with the perforations 28 after 85 the manner of a plugging operation.

The complete operation of the invention will be apparent from this detail description thereof, the oil feeding by gravity from the cup 11 through the line 12 causes the 90 oil to rise in the tubes 14 and into the journals 15 of the spindles 13 thereby lubricating the spindles. When it is desired to disconnect any spindle from the lubricating means, the stub tube 14 is pulled out of the 95 plugging opening 28 of the adjacent sleeve 25 and said sleeve revolved upon the line 12 to a point out of alignment with the adjacent oil outlet 27. In this manner, the valve 17 being closed in the desired tube 14, 100 the tube is disconnected and its sleeve 25 turned for shutting off the supply of oil. The sleeves 25 are capable of slight longitudinal shifting upon the line 12 and are readily secured against rotation by jam nuts 105 29 adjacent the opposite ends of the line 12 adapted for bearing against the adjacent sleeve 25 for forcing the sleeves together.

The hinged lid 30 is provided upon the reservoir 10 and it will be understood that 110 the flexibility of the tubes 14 permit the tubes to be unplugged from the perforations

28 without interfering with the coupling 16 and that the valves 17 are closed when disconnecting the tubes 14 from the sleeves 25 for preventing the back flow of any lubricant in the journals 15 through the valve tube of the spindle.

While the form of the invention herein set forth is believed preferable, it will be understood that minor changes may be made 10 therein without departing from the spirit and scope of our invention.

What we claim as new is:—

1. A spindle lubricator comprising a reservoir, a line pipe leading therefrom having 15 perforations, sleeves slidable and rotatable on said pipe having openings therein movable into registration with the perforations of the pipe line, said sleeves having interfitting ends forming fluid tight joints, means 20 for drawing said sleeves together to tighten

the joints between the ends, and flexible connecting pipes for the spindles adapted for removable insertion within the openings of the sleeves.

2. A spindle lubricator comprising a reservoir, a line pipe leading therefrom having 25 perforations, sleeves slidably and rotatably mounted on the line pipe having openings movable into registration with the perforations, means for flapping the sleeves together 30 to provide fluid tight joints between the meeting ends thereof and adapted for shifting the sleeves longitudinally of the line pipe, and flexible connecting pipes for the spindles adapted for removable insertion in 35 said openings.

In testimony whereof we affix our signatures.

WLADYSLAW GULA.
MICHAEL J. GLOGOWSKI.
